ANODE BUSHING FOR METAL-VAPOR ARC
CONVERTERSAlfred Siemens, Berlin-Charlottenburg, and Hans
von Bertele, Berlin-Wilmersdorf, Germany;
vested in the Alien Property CustodianApplication May 20, 1941, Serial No. 394,309
In Germany February 2, 1940

3 Claims. (Cl. 250—27.5)

Our invention relates to an anode bushing for metal-vapor arc converters—more in particular: high-voltage arc converters—comprising an insulator having a tubular extension through which the anode stem passes. Known anode bushings of this kind have the disadvantage that at the point where the anode stem leaves the tube of insulating material, high field concentrations are found which may lead to undesirable ionization phenomena. Known anode-bushing arrangements have often in addition the disadvantage that the insulating material is in contact with the hot anode body, and that as a consequence hereof, the structure of the insulating material may be destroyed.

The present invention avoids said difficulties in the case of an anode bushing for metal-vapor arc converters comprising a tube of insulating material through which the anode stem passes. The novelty covered by the invention consists in the fact that there is mounted between the anode body and the tube of insulating material a tube of graphite which surrounds the spot at which the anode stem leaves the tube of insulating material.

Application of the invention has the following beneficial results: in the first place, the tube of graphite constitutes a thermally insulating shield between the anode body and the tube of insulating material through which the anode stem must pass, and, in the second place, field concentrations at the point where the anode stem leaves the tube of insulating material will be avoided. In connection herewith, it is of advantage to reduce the outer diameter of the tube of insulating material at the lower end of this tube, and to insert this lower end into a corresponding recess of the graphite tube.

The invention further proposes to surround all live parts of the anode structure—except the front surface of the anode body—with a shielding member whose surface is continuous all around the anode-axis, and to apply to this shielding member a definite potential, it being necessary to arrange this member in a manner such that at any point its distance from the live parts will be shorter than the critical distance over which ionization by collision could still occur. It is desirable to apply to the shielding member a definite potential having a value comprised between the anode and cathode potential. Such a potential-value can be obtained, for instance, with the aid of a potential divider, or the shielding member can be connected to

the anode through an appropriately chosen resistor.

An example of an anode bushing designed in accordance with the present invention is illustrated on the drawing in which the figure is in sectional elevation of an anode bushing according to our invention.

An anode body 2 of graphite is attached to the lower end of an anode stem 1 whose upper portion is surrounded by a tube 3 of insulating material. In accordance with the present invention, a tube 4 of graphite is inserted between the anode body 2 and the tube 3 of insulating material. At its lower end 5, the tube 3 of insulating material has a reduced outer diameter, and this end 5 of the tube is inserted into a corresponding recess of the tube 4 of graphite. A small air-gap 8 is left open at the periphery of 5, between 5 and the tube of graphite.

The anode body 2 and the tube 4 of graphite are surrounded by a continuous shielding member 6, the shielded space being shut off at the lower end of the shielding member 6 by a grid structure 7. It is advantageous to have the upper portion of the shielding member 6 extend beyond the air-gap 8 left open between the tube 3 of insulating material and the tube 4 of graphite. The distance of the shielding member from the live parts 2 and 4 is shorter than the critical distance over which ionization by collision could still occur.

We claim as our invention:

1. An anode assembly for a vapor-electric arc converter comprising, an anode stem, a graphite anode head on said stem, a substantially tubular bushing of insulating material surrounding a portion of said stem, said bushing ending in spaced relation from said anode head and a substantially tubular body of graphite surrounding that portion of the anode stem between the anode head and the bushing, that portion of the bushing forming the end adjacent the graphite body being of less external diameter than this main body of the bushing, that portion of the graphite body adjacent the bushing having a recess of greater internal diameter than the diameter of the end of the bushing, said graphite body being telescoped over the end of the bushing and laterally spaced therefrom.
2. An anode bushing according to claim 1, characterized by the feature that all live parts of the anode structure—except the front surface of the anode body—are surrounded by a shielding member whose surface is continuous all

around the anode-axis and to which a definite potential is applied, the distance of this shielding member from the live parts being shorter than the critical distance over which ionization by collision could still occur.

3. In a vapor arc converter, an anode construction comprising an anode head, an anode stem supporting the head, an insulating bushing surrounding the stem said bushing ending in spaced relation to the head, a graphite tube surrounding the stem between the bushing and the head, a reduced portion on the end of the

bushing, a recessed portion on the graphite tube said recessed portion surrounding the reduced portion of the end of the bushing and being spaced therefrom, an annular shield surrounding the head and the tube and extending above the space between the tube and the bushing, said shield being spaced from the anode head and the tube a distance shorter than the distance in which ionization by collision will occur.
